BY *James E. Hagedorn*
his ATTORNEY

UNITED STATES PATENT OFFICE.

ERNEST M. GUILLAUME, OF WORCESTER, MASSACHUSETTS, ASSIGNOR TO THE FELTERS COMPANY, INC., OF BOSTON, MASSACHUSETTS, A CORPORATION OF MASSACHUSETTS.

WINDOW CHANNEL.

Application filed October 4, 1922. Serial No. 592,367.

To all whom it may concern:

Be it known that I, ERNEST M. GUILLAUME, a citizen of the United States, residing at Worcester, in the county of Worcester and State of Massachusetts, have invented certain new and useful Improvements in Window Channels, of which the following is a specification.

My invention relates to an improvement in window channels, and more particularly to a device of this character made of textile fabric, such as felt.

A device of this character has been made of a single strip of felt bent to form a channel. My improved channel is made of several strips of felt, stitched or otherwise secured together, and fashioned into a channel and fastened in that shape. This may be made in various forms.

20 In the accompanying drawings:

Fig. 1 is a view of the strip from which the channel is made;

Fig. 2 is an enlarged cross-section;

25 Fig. 3 is an end view of the completed channel;

Fig. 4 is a similar view showing it in a window frame with the two sides faced with a thin fabric, such as felt;

30 Fig. 5 is an end view of a slightly modified form of strip shown flat;

Fig. 6 is a similar view with the sides bent to form the channel;

Fig. 7 is an end view of still another form shown flat;

35 Fig. 8 is a view of the same with the sides turned to form the channel;

Fig. 9 shows the same applied to a window frame; and

40 Fig. 10 illustrates still another possible form.

The numeral 1 represents a backing strip, preferably of felt of suitable width and thickness; and 2, 3, and 4 are narrow bearing strips of felt fastened securely thereto by rows of stitches 5 or otherwise, and spaced apart lengthwise of the strip to form longitudinal channels 6. These channels are just wide enough to permit the edges to be folded to fold the sides as viewed in Fig. 3, with the inner edges 7 of the strips 2 and 4 resting upon the opposite sides of the intermediate strip 3. When bent into this form, the device is held in shape by the stitches 8 crossing the corners, as shown in Fig. 3, thus forming the permanent chan-

nel 9 at the center in which the plate-glass or window W slides.

In Fig. 4, a facing 10 of thin felt or other fabric is shown folded around the sides and held by stitches 11. This facing may 60 be used or not, accordingly as desired. In Fig. 4, the window channel is shown in position in the groove 12 of the window-frame 13.

In Fig. 5, the ends 1' of the main strip 65 are extended and folded over and held by stitches 14, thus making the sides of a single piece with the back of the channel. The central strip 3' is a separate strip held by stitches 5' as before. This form of channel is shown completed in Fig. 6.

In carrying out the invention, it would be quite possible to make a broad back strip 1" sufficiently wider so that the edges could be folded over to enclose the narrow side 75 strips 2" and 4", thus saving the necessity of using an extra strip for facing or lining.

A window channel of this character may be manufactured economically, for the reason that comparatively narrow strips of 80 felt may be used; and, furthermore, for the reason that there is no waste in the formation of the channel. Furthermore, no special machinery is required to manufacture it, as the strips composing it (if 85 stitched) may be securely attached by an ordinary sewing-machine.

I claim:

1. A window channel comprising a flexible backing strip having a finished face, 90 central and side bearing strips having finished faces and edges superimposed upon said backing strip and forming spaces between bearing strips, the backing strip adapted to bend at the spaces to impose 95 a finished edge of one bearing strip against the finished face of one adjacent bearing strip to form a channel of uniform qualities of strength due to the use of finished strips of material. 100

2. A window channel comprising a backing strip, central and side bearing strips superimposed thereon and having spaces between adjacent bearing strips, so arranged that bending the backing strip to form the 105 channel places the bending strain solely on the backing strip and completely closes the spaces by imposing an edge of a bearing strip against the face of an adjacent strip to form a channel, the bearing surfaces of 110

which are of substantially uniform qualities of resilience.

3. A window channel comprising a backing strip, a central bearing strip superimposed thereon, side bearing strips carried by the backing strip and spaced from the central strip, the bearing surfaces being substantially in the same plane and so arranged that bending the backing strip to form the 10 channel places bending strain solely on the backing strip and completely closes the spaces by imposing an edge of one strip against the face of an adjacent strip to form a channel, the bearing surfaces of 15 which are of substantially uniform qualities of resilience.

4. A window channel including four strips of material, one of which is relatively wide and thin, and the other three superimposed thereon with spaces between their adjacent edges, the outer edges of the wider backing strip folded around the outer edges of the narrow superimposed strips and brought approximately to the inner edges thereof, and lines of stitching through the 20 adjacent edges of the superimposed strips and extending through the wider backing strip, and stitching through the corners of the channel for holding the latter in form. 25

In testimony whereof I affix my signature. 30

ERNEST M. GUILLAUME.

Certificate of Correction.

It is hereby certified that in Letters Patent No. 1,482,132, granted January 29, 1924, upon the application of Ernest M. Guillaume, of Worcester, Massachusetts, for an improvement in "Window Channels," errors appear in the printed specification requiring correction as follows: Page 1, strike out lines 33 to 38, comprising brief description of Figs. 7, 8, and 9; line 39, for "Fig. 10" read *Fig. 7*; and that the said Letters Patent should be read with these corrections therein that the same may conform to the record of the case in the Patent Office.

Signed and sealed this 18th day of March, A. D., 1924.

[SEAL.]

KARL FENNING,
Acting Commissioner of Patents.
